UNITED STATES PATENT OFFICE

CLARENCE C. SHIPP, OF INDIANAPOLIS, INDIANA

OVERALL HOUSING FOR RADIATORS

Application filed September 25, 1929. Serial No. 395,012.

This invention relates to housings for steam radiators wherein a plurality of intermediate sections are surrounded on four sides with a sheet metal box which is open 5 at the top for the unobstructed discharge of hot air, and normally closed at the bottom by a box base which communicates with a wall box that extends to the outside of the building to supply fresh air to the radiator 10 box. Other sections have been provided at the ends of the radiator beyond the housed ones whose function is to directly warm the air in the room as utilized for heating the wall and window glass areas. Heretofore 15 these have been entirely unhoused thereby setting up erratic air currents and eddies, and throwing off too much direct radiant heat for the comfort of people sitting close to the radiator.

20 The object of this invention is to provide boxes for the end sections, open at the top and bottom, to cause air from the room to be driven in below, and discharged in a unitary column above thereby increasing the 25 driving power and circulation of the air in the room, and heating the cold air next to the floor.

A further object is to protect children in a school room from being accidentally 30 burnt by direct contact with the end sections, and shielding those sitting next to the radiator from the direct radiation from unhoused sections, and the object is to enhance the appearance of the radiator by enclosing all of 35 the sections in a single outside housing without front joints, while still segregating the middle sections in a separate box.

I accomplish the above, and other objects 40 which will hereinafter appear, by the means illustrated in the accompanying drawing, in which—

Fig. 1, is a front elevation, and partial vertical section, of a radiator equipped with my invention;

45 Fig. 2, is a top plan view of same with the top grid broken away in part;

Fig. 3, is a vertical section on the line 3—3 of Fig. 1; and

50 Fig. 4, is a perspective view of a portion of the box and radiator box base, broken

away in places to show the structural details.

Like characters of reference indicate like parts in the several views of the drawing.

A wall-box 5 is built into the outside wall 55 of the building, and through this, outside air is introduced into the room to be heated and ventilated. It has the usual louvers 6.

A radiator box-base 7 is formed out of sheet metal, rectangular in shape, and comprising a front, a back, two ends and a bottom. It is divided into three compartments 60 by the two partitions 8, 8, which extend above the level of the box sides to facilitate the assembly of an inner radiator box 9 which houses the intermediate radiator sections 65 that heat the air coming in from outdoors. The box-base has a rear sleeve extension 10 which fits telescopically on the wall box 5. This sleeve extension 10 has an outside flange 11 through which screws or nails are driven 70 into a wood frame 12, built into the wall, to retain the sleeve and box base in position, with a tight fit between the sleeve and the wall.

75 Located in the sleeve 10 is a damper 13 to control the supply of air coming in from out-of-doors. The damper is connected by a chain with a thermostat 14 located between the radiator and room wall.

80 Each of the two end compartments of the box-base 7 has a bottom opening 15 for the free entrance of air from below. The middle compartment may also have an opening which is closed by a door 16.

85 The door is shown partly open, but it is normally closed automatically by a spring 17.

The box-base ends and partitions have round holes 18 for the passage therethrough of the radiator bosses around the steam passage at the bottom of the radiator, and to enable the box-base to be assembled with the radiator after the radiator is set, I make the box-base in two longitudinally divided parts. The back part is first assembled and it has angle bars 19, inside at each end, by which the front part is joined to the rear one upon proper assembly, by the aid of suitable bolts, as shown.

95 The divided top edges of the end members and partition members are held in position 100

by channel bars 20. The channel bars 20 have bottom channels to receive the end and partition members therein, and they also have top channels. The top channels at the 5 partitions receive the edges of the inner radiator box 9 while those at the ends receive the edges of a radiator box 21. This box 21 surrounds all of the coils of the radiator and embraces the radiator box 9 within its interior so that a jointless and unbroken front is exposed to the public, thereby enhancing the appearance of the structure. The box 21 is joined to the box-base by the channel bars 20 in the manner as previously described. 10 15 The upper edges of the box 21 are finished with channel bar 23 having a top stiffening bead.

A metal grid 24 has an underside flange 25. The grid rests upon the top rolls 23 to 20 partially close the top openings to all three compartments of the radiator box below. It is held in place by the flange 25, which telescopes in the upper end of the box 21.

It will thus be seen that the middle sections of the radiator are housed separately from the sections at each end in a manner to circulate outdoor air therethrough, and that the end sections are also housed but in a manner which allows a free circulation of 30 the air of the room through their housings.

While I have here shown and described the best embodiment of my invention now known to me it is obvious that many changes are possible without departing from the spirit of the invention, and I therefore do not desire to be limited to that precise form shown or any more than is required by the appended 35 claims.

I claim:

1. The combination with a steam radiator 40 having a plurality of sections, of a box surrounding a plurality of the intermediate sections of the radiator, said box having an outdoor air supply at its lower end, sections at each end of the radiator outside of said 45 box, and a box housing the first box and all of the sections outside thereof, open at the top of all of the radiator sections and under the sections outside of the first box.

2. The combination, with a steam radiator 50 having a plurality of sections, of a box base in which all of the sections are assembled, said box base being divided by partitions into a major middle compartment and two minor end compartments, the middle compartment 55 having an outdoor air supply and the end compartments being open at the bottom and all of the compartments being open at the top, a radiator box seated on the box-base 60 partitions and front and back sides of the box base therebetween, and means resting on the box base for enclosing sections outside of the radiator box, said box and said means being open on top.

3. The combination, with a steam radiator

having a plurality of sections, of a box base in which all of the sections are assembled, said box base being divided by partitions into a major middle compartment and two minor end compartments, the middle compartment having an outdoor air supply and the end compartments being open at the bottom and all of the compartments being open at the top, a radiator box seated on the box-base partitions and front and back sides of the box base therebetween, and means resting on the box base for enclosing sections outside of the radiator box, said box and said means being open on top, the box base being in two longitudinally divided parts for convenience in assembly on an installed radiator, and means for removably uniting the parts. 70 75 80

4. The combination with a steam radiator having a plurality of sections, middle sections of which are housed on four sides and bottom and are supplied with outdoor air at the bottom, and other sections of which are housed to form a column through which room air may pass. 85

5. The combination, with a steam radiator having a plurality of sections, of a wall surrounding all of the sections, open at its top and bottom, and a box within the wall enclosing a major number of the sections and open at the top and normally closed at the bottom and having lower communication with outdoor atmosphere. 95

6. The combination, with a steam radiator comprising numerous sections, of a box surrounding all but the tops of a major portion of the intermediate sections, said box having an air conduit delivering outdoor air to the lower portion of the box and closures around the sections outside of the box, said last closures having openings at top and bottom for the free circulation of air. 100 105

7. A radiator box base having one or more vertical partitions, said base being in two longitudinally divided separable parts, channel bars uniting the divided ends and partitions of the box, a box seated on the box base housing all of the radiator sections, and a second box within the first seated on the channel bars of the partitions and means for supplying outdoor air to the box base under the second box. 110 115

8. For a steam radiator, a housing unit comprising a box vertically surrounding part of the radiator open at the top and having an air intake conduit fitting attached to its lower end, and walls extending from an end of the box surrounding an adjacent part of the radiator to define a vertically disposed passageway thereacross with openings at the top and bottom, said unit being adapted to direct room air across the said adjacent part of the radiator and to direct air discharging from said fitting across that part of the radiator within said box. 120 125 130 135

9. The combination with a steam radiator having sections, of a wall surrounding a plurality of said sections open at its top and bottom, and a compartment within the wall enclosing a number of the sections and open at the top and normally closed at the bottom and having lower communication with the outdoor atmosphere.

5 In testimony whereof I affix my signature.
